UNITED STATES PATENT OFFICE

ELMER A. SPERRY, JR., OF BROOKLYN, NEW YORK, ASSIGNOR, BY MESNE ASSIGNMENTS, TO SPERRY GYROSCOPE COMPANY, INC., A CORPORATION OF NEW YORK

AUTOMATIC STEERING FOR DIRIGIBLE CRAFT

Application filed July 7, 1922. Serial No. 573,280.

This invention relates to the navigation of all kinds of craft, more especially to the steering of dirigible craft, such as vessels, torpedoes and aeroplanes, which are guided by means of a rudder. More particularly, this invention relates to navigation of such craft by automatic means which operate to hold a vessel upon its course and prevent yawing movements by introducing counteracting forces upon incipient changes in heading of the craft.

This invention has for one of its objects keeping a ship on its true course by attacking yaw in the form of an automatic device where-by a mean helm position is not only constantly sought and found, but re-established for every wind, tide and current condition through which the craft is traveling. By mean helm position is meant the position of rest of the rudder which varies from the true central position due to such causes as variation in the revolutions of the propellers in multiple screw ships, weather, direction of tides, winds, current, etc. Any of these forces may operate to turn the craft constantly in one direction resulting in a small but appreciable deviation from the true or set course. To bring the craft back to its course would necessitate swinging the rudder outwardly through a comparatively large angular distance. As the ship reached its course, the rudder would be returned to initial position, but immediately the forces mentioned above would again turn the craft off its course to substantially the same extent, necessitating swinging the rudder outwardly a second time. A large yawing movement thus takes place. This process would be continuous as long as the forces were present, unless the mean position of the rudder were re-set with respect to the ship to a new, or virtual, central position which would neutralize the hereinbefore mentioned forces. Having once found the mean helm, or virtual center, position, it will be apparent that a substantial amount of yaw has been eliminated, and the yaw which takes place can be much more quickly attacked and corrected from the new base line of the rudder. This new mean position of the rudder allows the yaw to be corrected

and incipient changes of heading to be taken care of with less frequent shifts of the rudder, as well as less departure from the new base-line or virtual center, thus eliminating a large amount of drag and retardation upon the forward progress of the ship.

Hitherto, the setting of the mean helm position was left entirely to the experience of the helmsman or quartermaster. Consciously or unconsciously, the more experienced helmsmen constantly sought this mean helm position, and in doing so, introduced disturbances that could be avoided if this position could be scientifically determined and accurately maintained. The accurate and automatic determination of this particular rudder position is one of the principal objects of this invention.

Other objects and advantages will be in part obvious and in part specifically pointed out in the specification.

Referring to the drawings wherein I have shown what I now consider to be a preferred embodiment of my invention,

Fig. 1 is a front elevation of that portion of the steering apparatus, which is adapted to be placed in the pilot house of a vessel.

Fig. 2 is a plan view of a master course controller shown in Fig. 1.

Fig. 3 is a vertical section through the master course controller.

Fig. 4 is a wiring diagram of the course control mechanism.

Fig. 5 is a plan view of the automatic helm positioning means.

Fig. 6 is a vertical section through the device shown in Fig. 5.

Fig. 7 is a front diagrammatic view of the contact-controlling means forming part of the device in Fig. 5.

Fig. 8 is a plan view of a portion of the device of Fig. 5, showing the parts in different operative relation to set the rudder for helm.

Fig. 9 is a plurality of graphs or records illustrating the principles of navigation embodied in this invention.

Referring to Figs. 1 to 3, I locate, preferably in the pilot-house of the ship, a master controller 1 from which the rudder is automatically controlled. The system of course-

control by the mechanism of Figs. 1 to 4 inclusive is fully set forth and claimed in the copending application of Chester B. Mills, Serial No. 569,295, Automatic steering for 5 dirigible craft, and for a more complete description, reference should be had thereto, but it will be described here briefly. Said master controller is shown mounted on a stand 3 and performs the functions both of 10 a steering repeater compass and a master controller, the standard repeater compass card 10 cooperating with the settable course indicator 11. The indicator, or pointer 11, is mounted upon a shaft 12 concentric with 15 card 10, controlled from a repeater motor 13. The entire mechanism is enclosed in a casing 9 having the usual glass cover 14 and bezel 15. The card is rotated by the motor 13 through gears 16, 17 to rotate shaft 18 and 20 gear 19 thereon, gear 19 meshing with gear 20 on a bushing 21 journalled in a partition plate 22, said card being fixed to the upper end of said bushing.

To set the pointer relative to the repeater 25 card the usual handle 30 may be provided which operates by means of bevel gear 31 a differential comprising upper gear 32 and lower gears 33, 34, the gears 31 and 34 meshing with gears 35 and 36 of a planetary 30 member 37 fixed to shaft 18. Since shaft 18 is rotated by the repeater motor, operation of handle 30 will rotate gears 35 and 36 about their axes to rotate gear 32 and gear 40 fixed thereto, said gear 40 meshing with gear 41 35 fixed to the pointer shaft 12. Fixed to gear 32 is a trolley 50 meshing with contact strips 51, 52 arranged in the form of rings, here shown positioned to one side of the casing. It will be obvious that when a new course is set by 40 handle 30, or when the ship turns off its course, so that trolley 50 is rotated by the repeater motor along the contact strips 51, or 52, there is set in operation the following means to move the ship to a new course 45 or bring it back after it has moved off its course.

Any deviation of the ship from its course 50 will cause rotation of gear 32, and hence, of the card 10 and the trolley 50. Referring to Fig. 4, it will be observed that the trolley 50 is in the form of a lever which carries three contacts 68, 69 and 70, the first two upon one arm thereof and the last upon the other arm. Contacts 68 and 70 engage 55 contact strips 51, 52, 71, 72, 73 and 74 of a contact ring, while contact 69 engages a separate contact 76. The operation of the device is as follows:

Case 1.—Assume slight yawing movement 60 in a clockwise direction insufficient to move contact 68 off insulation 54 between contact strips 51 and 52. A circuit is then established from main lead 140, contacts 69 and 76, to an auxiliary control device 25. Said device 65 comprises brushes 26, 27, 28 and 29, con-

trolled from a repeater motor 39 similar to motor 13, and cooperating with a commutator ring or commutator 38. Said commutator has live segments 43 and 44, the former 70 cooperating with brushes 26 and 27, and the latter cooperating with brushes 28 and 29. All of said brushes normally contact with insulated strips 45.

So that in the case here discussed, brush 28 engages contact 44, and the circuit continues through said contacts 80, 81, and relay coil 82, closing a circuit through coil 83 of a motor 84 to drive the rudder in clockwise direction and move the ship counterclockwise to counteract the yaw. The end of the 75 rudder 46 is provided with a block 85 which closes a set of contacts 86, when said rudder moves as desired, to break the circuit through field coil 83 by energizing relay 80. The rudder is held in this position until the ship 80 turns back counterclockwise sufficiently to move brush 29 into engagement with contact 44 to establish a circuit through relay contacts 87, 88 and relay coil 89 which closes a 85 circuit through oppositely-wound coil 90 of motor 84 to drive the rudder counterclockwise and turn the ship clockwise. When the rudder engages contacts 91, it breaks the circuit through coil 90 by energizing relay 87. These 90 small oscillations of the rudder between contacts 86 and 91 are thus continued during the small yawing movements of the ship to counteract such movements. The relays 82 and 89 are normally open, and when closed, serve to 95 close the circuit through the motor from main lead 140 to main lead 141.

Case 2.—Assume greater deviations of the ship so that contact 68 engages contact 51 or 52, contact 70 does not move out of engagement with contact 74, and contact 69 does not move out of engagement with contact 76. If the ship yaws clockwise, a circuit is established from main lead 140, contacts 68, 51, 43, 26, relays 81 and 82 to coil 83 of the motor, and another circuit from contacts 69, 76, 44, 28, relays 80, 81, 82, also to coil 83 to drive the rudder clockwise and turn the ship counterclockwise to counteract the yaw. When the rudder closes contacts 92, it forms a circuit 100 including contacts 70 and 74 to break the circuit through coil 83 by energizing relay 81.

Trolley 50 rotates through the full angle of deviation, but the commutator of the auxiliary control device 25 is limited to a very small movement by stops (not shown) and a slip-friction connection between the commutator and its shaft, which permits the shaft to continue to rotate after the commutator has been stopped.

Because of the small movement of the commutator, as soon as the ship starts to turn clockwise, brush 26 moves off contact 43 while contact 68 is still on contact 51, and brush 28 moves off contact 44. Brush 29 now engages contact 44 to establish a circuit through the 125

lower relays and coil 90 to drive the rudder counterclockwise until it engages contacts 91 to break the circuit through coil 90 by energizing relay 87. The ship continues its counterclockwise movement back to its course under its own momentum.

If the ship yaws in counterclockwise direction, the lower set of relays is first energized until the rudder engages contacts 93. As soon as the ship starts to turn back, the upper set of relays is energized to return the rudder, until the latter engages contacts 86 to energize relay 80.

Case 3.—Assume in case 2 that the deviations are sufficient to move contact 70 into engagement with contact 72 or 73. The operation would be the same as in case 2, except that the circuits which control the limiting positions of the rudder would now be from contact 70, contact 72 or 73, to contacts 94 or 95 instead of 92 and 93, and thus permit a greater swinging of the rudder corresponding to the greater angle of deviation of the ship.

Case 4.—Assume that handle 30 is operated to move trolley 50, or that the ship yaws to an unusual extent, such that contact 69 moves beyond contact 76 and that contact 70 moves beyond contact 72 or 73. Contact 68 still engages contact 51 or 52. Assume that counterclockwise movement of the ship is necessary to bring it to its new course. A circuit is established which includes contacts 68 and 51, relays 81 and 82 to coil 83 to drive the rudder clockwise and turn the ship counterclockwise. When the rudder reaches limiting contacts 96, it breaks the circuit through coil 83 by energizing relay 81. As the ship starts to turn counterclockwise, however, no circuit is established through coil 90 to return the rudder, as in preceding cases, since contact 69 is off contact 76. The rudder therefore, holds its extreme position, causing the ship to turn rapidly and continuously, until, as it nears its course, contact 69 engages contact 76, and thereafter the device operates as in the other cases. The rudder is returned before the ship reaches its course, allowing the momentum of the ship to bring it to its course.

When the ship is to be turned clockwise, the lower set of relays energizes coil 90 to drive the rudder counterclockwise, until it engages stop 97 to energize relay 88 and break the circuit. When contact 69 engages contact 76, the upper set of relays is effective to energize coil 83 and return the rudder.

It is thus apparent that for small deviations, the device operates as in cases 1, 2 and 3, to swing the rudder outwardly a distance proportional to the deviation, and as soon as the ship starts back, the rudder is returned, the momentum of the ship being sufficient to carry it to its course. For large deviations, however, the rudder is held in extreme position, until the ship approaches its course.

Before the ship reaches its course, the rudder is returned and the momentum thus imparted is sufficient to bring the ship to its course.

It will also be apparent that it is immaterial how trolley 50 comes into engagement with the contact strips, whether through yawing of the ship or through operation of handle 30 to set a new course.

An alarm 98 energized by its own source of energy 99 may be provided in circuit with trolley 50 and contacts 71, so that an alarm is sounded whenever such unusual turning or yawing of the ship takes place, as will cause trolley 50 to engage said contacts. The alarm may thus serve to warn against unusual atmospheric or tidal conditions or faults arising from the ship proper.

The motor 84 may be arranged to control a steering mechanism, such as a telemotor of the usual type. Thus the motor shaft 110 may operate a pinion 111 which engages two racks 112 and 113 on opposite sides thereof. Said racks operate as plungers in cylinders 114, 115, so that rotation of pinion 111 will cause one plunger to move inwardly in its cylinder and the other plunger to move outwardly. This causes a displacement of the fluid to one side which is transmitted by pipes 116, 117 connected to cylinders 114, 115, respectively, to the opposite sides of the steering engine 120, 121, which is geared to the sector 122, integral with the rudder. Further details of the steering engine are not essential for the purposes of disclosing the present invention, since such engines are standard commercial units and well known in the art.

It will be observed that it is the rudder that controls the course control mechanism by a follow-up mechanism. This follow-up mechanism is therefore independent of the steering engine used to operate the rudder, and hence all errors arising in the telemotor, its gearing transmission, etc. are eliminated so far as the course control mechanism is concerned.

Motor 65 is a series motor, one of the characteristics of which is the picking up in speed the longer it runs, within a given interval. Thereafter, as the counter E. M. F. builds up, the speed diminishes. This action of the motor is desirable because for small movements of the rudder only the initial, comparatively slow speed of the motor is utilized, but where the rudder is to be operated through greater distances, the motor picks up speed the longer it rotates and thus drives the rudder more rapidly than for small angular distances. It may occur, however, that the rudder is operated through so great an angular distance that the motor rotates long enough for the second phase, i. e., the diminishing speed, to set in. To prevent such diminution in speed, there may be provided a relay 125, the coil 126 of which is in series with a resistance 127 in the motor circuit.

When the counter E. M. F. builds up, relay 125 is operated to short circuit resistance 127 and thus increase the speed of the motor. The system may be made sensitive by employing a plurality of relays similar to 125 adapted to be operated successively to cut out an increasing amount of resistance and thus provide for acceleration of the motor corresponding to the length of time during which it is operated continuously.

The rudder may be operated either from the motor 84 as described through link 55 and shaft 56, or by the usual steering wheel 57 operated by hand. The latter may be found desirable at times, as when entering or leaving port. For this purpose a clutch 58 may be provided for throwing in or out the motor drive.

If a vessel yaws equally from side to side, the rudder will be operated through equal angular distances to either side of the true course, in order to counteract these yawing movements. Due, however, to such forces as the direction of the wind, the variation in the revolutions of the propellers in multiple screw ships, the tides and currents, the vessel is often continually forced off its course in one direction. The rudder instead of being operated equally to either side of the true course must now be operated through a segmental portion whose central axis is considerably to one side of the true course, thus causing the ship to follow a new course which slightly deviates from the true course. This variation of the mean position of the rudder from the true mean position (i. e., the true course of the ship) is termed the "helm."

In the present invention as hereinbefore described, to counteract these additional forces, the rudder would be thrown outwardly an angular distance sufficient to bring the ship back to its course. The rudder would be returned shortly before the ship reached its course, with the result that the ship would again be turned off its course by these extraneous forces, necessitating operation of the rudder in the same direction again. There thus results a continuous yawing movement of the ship mostly to one side of the true course, and to avoid repeating this process as long as the extraneous forces are operative, means are provided for preventing this yaw by changing the relationship which exists between the compass and the rudder and automatically determining the helm, i. e., establishing a virtual center which is such a position of rest of the rudder varying from the true center position, as will be sufficient to counteract the effects of the extraneous forces and keep the ship on its true course. In other words, where heretofore the indications of the ship's course on the compass corresponded to the true central position of the rudder, the same indications will correspond to the mean position of helm.

For automatically determining the mean position of helm, the rudder 46' (see Figs. 5 to 8) is connected by means of an adjustable link 150 to a segment 151 mounted upon a vertical shaft 152 journaled in a boss 153, forming part of a base 154. Fixed upon said shaft between segment 151 and boss 153 is a second and larger segment 155. The latter carries operating links 156, 157 extending therethrough, and preferably having rollers 158 at their lower ends, which are normally pressed into engagement with base 154 by springs 149. Said operating links are adapted to cooperate with cams 160 and 161 positioned on said base, said links and cams being so positioned that equal angular movements of segment 155 to either side of center line Y—Y will cause operating link 156 to engage cam 160 or operating link 157 to engage cam 161 to force the respective link upwardly and operate a ratchet 165 or an oppositely toothed ratchet 166, respectively. Said ratchets are fixed to the ends of a shaft 168 journaled upon segment 155 and having a worm 170 formed thereon meshing with a rack 171 on the periphery of segment 151. It will thus be seen that rudder 46' is movable integrally with segment 155, as well as relatively thereto, through link 150, worm 170 and gear 171 and any movement of the rudder will cause corresponding movement of segment 155. Assuming that there are no extraneous forces, the rudder 46 moves equal angular distances to either side of line X—X to counteract yawing movements of the ship. Segment 155 therefore also moves equal angular distances to either side of line Y—Y. If these distances are very small, links 156, 157 will not reach cams 159, 160, but if the distances are comparatively large, each operating link will engage its respective cam. Operating link 156 will engage cam 160 and be raised against the action of spring 149 to cause a pawl member 175 carried at the upper end of the link to engage ratchet 165 which is thus operated to rotate worm 170 and so move rudder 46 relative to segment 155. As the rudder moves to the opposite side of line X—X, link 157 engages cam 161 to cause a pawl 180 carried by said link to operate ratchet 166 in the reverse direction to ratchet 165 and so restore the original relative positions of the rudder and segment 155. Springs 177 may be provided to engage the pawls and move them out of engagement with the ratchets when the operating links are lowered.

Assume, now, that extraneous forces are acting upon the ship, necessitating movement of the rudder toward the right, counter-clockwise, to bring the ship back to its course. In so moving the rudder to the right, link 156 engages cam 160 to operate ratchet 166 and move segment 151 and rudder 46 to the right relative to segment 155. When the ship nears its course, the rudder is returned until seg-

ment 155 is on its center line Y—Y, but the rudder is now positioned slightly to the right of X—X. Instead of swinging to the left of line Y—Y, as in ordinary yawing, the extraneous forces again move the ship off its course, before link 157 has engaged cam 161 to operate ratchet 165, necessitating operation of the rudder to the right to operate ratchet 166 again. The continued operation of the ratchet 166 moves the rudder continuously to the right of center line X—X and relative to segment 155, thus giving the rudder a permanent set or "helm" off its true center sufficient to counteract the effect of the extraneous forces. The ship is thus held upon its course except for those yawing movements which give rise to equal angular movements of the rudder to either side of its mean position of "helm" indicated by line Z—Z in Fig. 8, causing equal operation of ratchets 165 and 166 to maintain the relative positions of the rudder and segment 155. The line Z—Z is the new or virtual center position of the rudder and there is thus avoided the necessity of repeatedly swinging the rudder from line X—X to line Z—Z, to counteract the extraneous forces which necessitate the setting of helm. Large yawing movements of the craft are therefore prevented by this automatic helm positioning device.

If extraneous forces should now operate on the ship, to turn it off its course in a direction so as to necessitate repeated operation of the rudder to the left, clockwise, ratchet 165 will be operated more frequently than ratchet 166 to move the rudder to the left relative to segment 155. Thus, any extraneous force which would tend to throw the ship steadily off its course is automatically compensated by the positioning of helm effected by the unequal operation of ratchets 165 and 166, to counteract such force, so that steering of the ship may progress as if such force were not present. The mean position of "helm" is thus the base line from which the steering mechanism operates. The device is thus constantly setting itself to the scientifically accurate virtual center or mean position of "helm" for maintaining the true course.

The adjustable link 150 comprises two portions connected by a turn-buckle 190 which permits the initial relative positions of the rudder and the segment 155 to be adjusted to take care of such variations as are due to the particular vessel, or any other known variations.

By referring to the graphs of Fig. 9, the principles of navigation embodied in this invention may be illustrated. In all of these graphs the rudder movements are recorded. Referring to graph 1, it will be seen that the rudder was operated for small angular distances (shown here as about 2°) which would correspond to movements between contacts 86

and 91, or sufficient to counteract ordinary yaw. The graph shows an occasional rudder movement beyond these points, but on the whole the yaw takes place equally to either side of the actual center X—X.

The condition where an extraneous force sets in to turn the craft constantly off its course is illustrated in graphs 2 and 3, where a force is acting to turn the craft constantly toward the right. Graph 2 is a record of the rudder movements which are due to an inexperienced helmsman, or to automatic steering means which makes no provision for automatic determination of helm. Between the points A and B the vessel yawed normally. Thereafter, forces tended to turn it off its course constantly toward the right. The helmsman or automatic steering mechanism hereinbefore mentioned threw the rudder outwardly (to a point here shown as 8°) and brought the craft back to its course, whereupon the rudder was returned to center position X—X, but no sooner did the craft reach its course, than it was turned off toward the right again, necessitating operating the rudder outwardly again, through 8° in the same direction. This operation was continued as long as the said force acted to turn the ship steadily to the right.

Referring to graph 3, there is illustrated the manner in which an automatic steering mechanism equipped with the automatic mean helm determining mechanism of this invention met the situation or condition present in graph 2. The portion A—B corresponds to the portion A—B of graph 2. The portion B—C, however, illustrates the operation of giving the craft "helm". Instead of returning the rudder (which has been swung outwardly the same 8° as in (graph 2) to center line X—X, it is stopped short of said line by constantly increasing angular distances until a new center line position was found. In the graph this line is shown as 6° to the right of the actual center X—X, indicating that by offsetting the rudder 6°, the force which tends to turn the craft steadily off its course is neutralized. Thereafter, ordinary to and fro movements of the rudder (shown here as approximately 2°) takes place to either side of the virtual center Z—Z, instead of the large rudder movements (about 8°) in graph 2 under the same conditions. This of course also means that the amplitude of the yaw is correspondingly reduced.

The follow-back contacts, which in the diagrammatic representation of Fig. 4 are shown as engaged directly by the bar 85 on the rudder, are here mounted on base 154 and so positioned as to be engaged by the bars 178 and 179 on the segment 155, since the latter always maintains the same initial position relative to said contacts, while the initial position of the rudder varies according to the mean position of "helm". Said bars 178, 179 are

spaced in planes one above the other. The contacts 91, 93, 95 and 97 are arranged in the path of bar 178, while contacts 86, 92, 94 and 96 are arranged in the path of bar 179.

5 In accordance with the provisions of the patent statutes, I have herein described the principal of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

10 20 Having herein described my invention what I claim and desire to secure by Letters Patent is:

1. In an automatic steering device, the combination with the compass governed controller and rudder, of means responsive to persistent yawing movements of the ship in one direction from the course, and means operated thereby for changing the relation between the compass controller and rudder 25 to centralize the oscillations of the controller and rudder.

2. In combination with a steering mechanism of a dirigible craft including a rudder, a control member actuated in accordance 30 with movements of said craft on opposite sides of its course, adjustable means connected between said rudder and said member whereby the relation of said rudder with respect to said member and said craft may 35 be varied, and means for automatically actuating said adjustable means upon persistent movements of said member to one side of its central position to change the normal relationship between the rudder and control member for the purpose specified.

3. In combination with the steering mechanism of dirigible craft, means for counteracting movements of the craft to either side of its course and means operated by the unequal movements of the craft on opposite sides of its course for automatically altering the mean position of the rudder to equalize said movements.

4. The combination with the automatic steering mechanism for dirigible craft including a compass and automatic means governed thereby for actuating the rudder, of means for altering the relationship between the compass and rudder, and automatic 55 means brought into action by successive unequal movements of steering mechanism to one side of the neutral position for operating said first-named means.

5. The combination with automatic steering mechanism for dirigible craft having a

70 compass governed controller and a rudder, of means for reducing yaw and rudder movements, said means comprising a member movably connected to said rudder and craft, means actuated in accordance with the movements of the craft on opposite sides of its course for operating said member, an intermediate adjustable member connecting said first-named member and rudder, and means actuated by unequal excursions of said member for operating said adjustable member to change the relation between the rudder and controller for the purpose specified.

75 6. The combination with automatic steering mechanism for dirigible craft having a compass governed controller and a rudder, of means for preventing deviation from the course by side winds and the like, said means comprising a member movably connected to said craft, adjustable means connecting said member and rudder, and means actuated in accordance with unequal movements of the craft on opposite sides of its course for operating said adjustable means to change the normally fixed relationship between the rudder and controller.

80 7. The combination with automatic steering mechanism for dirigible craft having a rudder, of means for automatically determining the mean position of helm, said means comprising a member movably connected to said rudder and craft, and means whereby unequal movements of said member on opposite sides of its central position operates said member and rudder to set a new base 90 line for said rudder.

85 8. The combination with automatic steering mechanism for dirigible craft having a rudder, of means for reducing the rudder movements, said means comprising a member movably connected to said rudder and craft and means whereby unequal movements of said member on opposite sides of its base line operates said member and rudder to set a new base line for said rudder.

90 9. The combination with automatic steering mechanism for dirigible craft having a rudder, of means for automatically determining the mean position of helm, said means comprising a member movably connected to said rudder and craft and means whereby unequal movements of said member on opposite sides of its base line operates said member and rudder to set a new base line for said rudder, the deviation of said new base 100 line from the old base line being in proportion to the degree of inequality of said rudder movements.

10. In automatic steering mechanism for dirigible craft having a rudder, the combination with a master controller of means for altering the relation between the rudder and controller to alter the neutral position of the former, said means comprising mechanism whereby unequal movements of said 105 110 115 120 125 130

rudder on opposite sides of its neutral position moves the rudder with respect to said controller in a direction of said greater rudder movements from said position.

5 11. In automatic steering mechanism for dirigible craft having a rudder, the combination with a master controller of means for altering the relation between the rudder and controller to alter the neutral position of the former, said means comprising mechanism whereby unequal movements of said rudder on opposite sides of its neutral position moves the rudder with respect to said controller in a direction of said greater rudder movements from said neutral position.

10 12. The combination with automatic steering mechanism for dirigible craft having a rudder, of means for reducing the rudder movements, said means comprising means for offsetting the neutral position of said rudder with respect to said automatic steering mechanism when the rudder is continuously operated more to one side of its normal neutral position than to the other and means 15 for offsetting the neutral position in the opposite direction when the rudder is continuously operated more to said other side of its said normal neutral position than to the first side, for the purpose specified.

20 13. The combination with automatic steering mechanism for dirigible craft having a rudder, of means for automatically determining the mean position of helm, said means comprising a member connected to said rudder, a second member adjustably connected to said first member, and means for operating said first member relative to said second member, when the rudder operates to one side or the other of its base line, to move said first member and rudder in a corresponding direction relative to said second member and offset the base line in said direction.

25 14. The combination with automatic steering mechanism for dirigible craft having a rudder, of means for automatically determining the mean position of helm, said means comprising a member connected to said rudder, a second member adjustably connected to said first member, and means for operating said first member relative to said second member, when the rudder operates to one side or the other of its base line, to move said first member and rudder relative to said second member to offset the base line.

30 15. The combination with automatic steering mechanism for dirigible craft having a rudder, of means for automatically determining the mean position of helm, said means comprising a member connected to said rudder, a second member adjustably connected to said first member, a plurality of mechanisms for moving said first member and rudder relative to said second member and means for operating one of said mechanisms 35 to offset the base line of the rudder in one

direction when said rudder is operated to one side of said base line and for operating the other of said mechanisms to offset the base line in the other direction when said rudder is operated to the other side of said base line. 70

16. The combination with automatic steering mechanism for dirigible craft having a rudder, of a member connected to said rudder, a second member adjustably connected to said first member, means for varying the relation between said two members, including a plurality of mechanisms for moving said first member and rudder relative to said second member, one of said mechanisms operating said means to offset the base line of the rudder in one direction and the other of said mechanisms operating said means to offset the base line in the other direction and means for operating one of said mechanisms when said rudder is operated to one side of said base line 75 80 and for operating the other of said mechanisms when said rudder is operated to the other side of said base line.

17. The combination with automatic steering mechanism for dirigible craft having a rudder, of a member connected to said rudder, a second member adjustably connected to said first member, gearing between said members, a plurality of mechanisms for operating said gearing to move said first member and 90 rudder relative to said second member, one of said mechanisms operating said gearing to offset the base line of the rudder in one direction and the other of said mechanisms operating said gearing to offset the base line in the other direction, said mechanisms each comprising a pawl and ratchet and an operating member carried by said second member for operating said pawl and ratchet and means for operating one of said mechanisms 95 100 when the rudder is operated to one side of the base line and for operating the other of said mechanisms when the rudder is operated to the other side of said base line.

18. The combination with automatic steering mechanism for dirigible craft having a rudder, of means for automatically determining the mean position of helm, said means comprising a member connected to said rudder, a second member adjustably connected to said first member, gearing between said members, a plurality of mechanisms for operating said gearing to move said member and rudder relative to said second member, one of said mechanisms operating said gearing to offset the base line of the rudder in one direction and the other of said mechanisms operating said gearing to offset the base line in the other direction, said mechanisms each comprising 115 120 a pawl and ratchet and an operating member carried by said second member for operating said pawl and ratchet and a plurality of cams, each of said operating members being adapted to engage one of said cams to be operated 125 130

- thereby when said rudder is operated to one side or the other of the base line.
19. The combination with automatic steering mechanism for dirigible craft having a rudder, a member movably connected to said rudder and craft, and means actuated in accordance with the movements of the craft on opposite sides of its course for operating said member and setting said rudder, said member being adjustably connected to said rudder to vary the position of the rudder relative to the steering mechanism.
20. In an automatic steering mechanism for dirigible craft having a rudder and course indicating means, means for setting said rudder in predetermined relation to said indicating means, and means controlled by the movements of the rudder for automatically changing the relationship between said indicating means and said rudder.
21. In an automatic steering mechanism for dirigible craft having a rudder and course indicating means, said rudder being normally set in predetermined relation to said means, means whereby said rudder is operated to counteract movements of the craft off its course, and means for automatically changing the relationship between said indicating means and said rudder when said craft is turned off its course to one side to a greater degree than to the other side thereof.
22. The combination with a dirigible craft having a rudder, of automatic steering means therefor including a follow-back system from said rudder to said means, and means for altering the position of the rudder with respect to said follow-back system to reduce rudder movements.
23. The combination with the automatic steering mechanism for dirigible craft including a compass and automatic means governed thereby for actuating the rudder, of a follow-back system between the rudder and said means, and means for altering the position of the rudder with respect to said follow-back system to change the relation between the compass and the rudder.
24. In an automatic steering device, a means for preventing deviation of a ship from its course comprising means responsive to yawing of the ship to one side of the course, and means operated by said second named means for correcting the relative positions of the controller and rudder to maintain the ship on its original course.
25. In an automatic steering device for ships, a means for preventing the deviation of a ship from its course, comprising the combination with the compass and rudder, of means responsive to yawing of the ship to one side of its course, and means responsive thereto for changing the relation between the compass and rudder to maintain the ship on its original course.
26. In an automatic steering device, a means for preventing deviation of a ship from its course, comprising means responsive to yawing of the ship to one side of the course, and automatic means operated by said second named means for correcting the set course in proportion to the extent of preponderance of yaw to one side of the original course.
- In testimony whereof I have affixed my signature.
- ELMER A. SPERRY, JR.
